US0D1070368S

(12) **United States Design Patent** (10) **Patent No.:** **US D1,070,368 S**
(45) **Date of Patent:** **** Apr. 15, 2025**

(54) **SHEET MATERIAL**

(71) Applicant: **SCHATTDECOR AG**, Thansau (DE)

(72) Inventor: **Christian Zaha**, Traunstein (DE)

(73) Assignee: **SCHATTDECOR AG**, Thansau (DE)

(**) Term: **15 Years**

(21) Appl. No.: **29/796,866**

(22) Filed: **Jun. 28, 2021**
